UNITED STATES PATENT OFFICE.

JOSEPH W. JONES, OF CORNING, NEW YORK, ASSIGNOR TO INGERSOLL-RAND COMPANY, OF JERSEY CITY, NEW JERSEY, A CORPORATION OF NEW JERSEY.

AUTOMATIC SPEED REGULATOR.

Application filed September 21, 1923. Serial No. 663,975.

To all whom it may concern:

Be it known that I, JOSEPH W. JONES, a citizen of the United States, and a resident of Corning, county of Steuben, and State of New York, have invented a certain Automatic Speed Regulator, of which the following is a specification, accompanied by drawings.

This invention relates to an automatic speed regulator particularly adapted for regulating the speed of the driving engine of a compressor.

One object of the invention is to regulate the speed of the engine, which may be an internal combustion engine, in accordance with the requirements for air, and for this purpose, the regulator is preferably subject to the discharge pressure of the compressor, at all times, which begins to take effect or act on the regulator, at a pre-determined pressure, so that the engine speed is reduced or increased as the demand for air decreases or increases.

The regulator preferably includes a centrifugal governor for the driving engine, and another object of the invention is to operatively connect the fluid operated regulating device with the centrifugally operated governor in such manner that the action of the centrifugally operated governor tends to counteract the action of the fluid operated device.

The invention is shown in one of its preferred forms in the accompanying drawings, which is a diagrammatic side elevation of a portable combustion engine driven compressor unit, partly in section, sufficient parts being shown to illustrate the invention.

Referring to the drawing, the invention is shown in connection with a portable compressor unit, in which the compressor A mounted on the frame B, having the wheels C, is driven by any suitable combustion engine D. The invention, however, is applicable to stationary as well as portable units. The air receiver E for the compressor, and the gasoline tank F for the combustion engine, may be mounted in any suitable manner on the frame. The main driving shaft of the combustion engine D and the crank shaft G of the compressor, are coupled by any suitable coupling H.

The combustion engine is provided with

a suitable centrifugal governor, mounted on the counter shaft J, suitably geared to the engine shaft K.

The weighted governor arms L, in this instance, are pivoted on the spider O, and are adapted to bear against the plate P, slideable on the counter shaft J, which in turn moves the lower end Q of the governor lever R outwardly about the pivotal point S, as the governor arms fly outwardly with increased speed of the engine. The upper end of the lever R is suitably connected by means of the rod T and other operative connections to be described, to the throttle U of the combustion engine, so that upon an increase of speed of the engine beyond a pre-determined degree, the throttle U will automatically move towards closed position and the speed brought back to the desired point.

Means are provided for setting the governor whereby the speed of the engine may be limited to a pre-determined maximum, and in this instance, a compression spring V is held between the cap W on the lever R and the cap X on the end of the adjusting set screw Y, which in turn is mounted within a guide Z connected to a suitable bracket b on the engine frame. The tension of the governor spring V determines the maximum speed of the engine.

In accordance with one feature of the invention, an automatic regulating device is provided for controlling the speed of the engine in accordance with the requirements for air, and this regulating device reduces the speed of the engine as the demand for air decreases, by actuating the engine throttle U.

In the present instance and as a convenient form of regulating device adapted to be mounted on the combustion engine, a cylinder a may be secured to the same bracket b on which the spring guide Z is mounted, and a fluid pressure connection, in the form of a pipe c is connected between the said cylinder a and the air receiver E of the unit. A plunger d in said cylinder a, is in this instance under substantially constant air pressure from the receiver E and a bell crank lever e pivoted at f to the bracket b, has one arm bearing upon the plunger d, the other arm of said bell crank lever being pivotally connected at the point g to a link

h which is in turn connected at the point *j* to the rod *T*, connected to the upper end of the governor arm *R*. A lever *k* is pivotally connected at the point *o* intermediate the length of the link *h* and is also pivotally connected to the throttle *U* of the engine. By this means, movement of the governor arm *R* as heretofore described, will transmit motion directly through the rod *T*, link *h* and lever *k* to the throttle *U*, for directly controlling the speed of the engine through the action of the centrifugal governor.

An adjustable stop *p* on the bracket *b* limits the rocking movement of the bell crank lever *e* about its pivot *f*, due to the action of the plunger *d* in the air cylinder *a* of the regulating device. A spring *q* is adapted to be compressed between one arm of the bell crank lever *e* and an adjustable stop *r* also mounted in a portion of the bracket *b*. The function of the adjustable spring *q* is to permit the regulating device to be set for operation under a given discharge pressure of the compressor.

In the operation of the device, as described, let it be assumed that the demand for air decreases so that the speed of the engine should be reduced accordingly. The increased pressure built up in the air receiver *E* will force the plunger *d* outwardly in the cylinder *a*, and rock the bell crank *e* about its pivot *f*, which will move the pivotal connection *g* of the link *h*, in a direction to actuate the throttle *U* towards closed position. Under such circumstances, the pivotal point *j* of the link *h* at the connection to the governor rod *T*, will remain substantially stationary and form the fulcrum about which the link *h* is moved, in order to actuate the throttle. By this means, the regulating device controls the speed of the engine in accordance with the demand for air. As the demand for air increases again, the pressure in the receiver *E* will be reduced and the bell crank *e* will be rocked under the influence of the spring *q* to force the plunger *d* into the cylinder *a*, at the same time moving the throttle *U* towards open position for increasing the speed of the engine to meet the increased demand for air. Under the first condition specified and assuming that the speed of the engine has been reduced by the partial closing of the throttle *U*, the governor arms *L* of the centrifugal governor, will move towards each other, thus permitting the governor arm *R* to be rocked on its pivot *S* under the influence of the governor spring *V*, and the governor rod *T* will be moved in a direction to rock the link *h* about the pivotal point *g* which in this instance remains substantially stationary, and the lever *k* connected to the throttle *U* will be moved in a direction tending to open the throttle *U* so that the action of the centrifugal gov-

ernor tends to counteract the action of the fluid operated regulating device.

Under the second condition specified and assuming that the speed of the engine has been increased again by the partial opening of the throttle *U*, the governor arms *L* of the centrifugal governor will move away from each other, thus causing the governor arm *R* to be rocked on its pivot *S* under the influence of the increased centrifugal force of governor arms *L* and the governor rod *T* will be moved in a direction to rock the link *h* about the pivotal point *g* which in this instance remains substantially stationary, and the lever *k* connected to the throttle *U* will be moved in a direction tending to close the throttle *U* so that the action of the centrifugal governor tends to counteract the action of the fluid operated device.

This compensating action of the governor parts is desirable in order to secure smooth regulation by eliminating the tendency of either to travel too far when set in motion by a change of speed or of pressure. It insures uniform regulation of the speed in accordance with the demand for air.

I claim:

1. In a compressor unit, the combination of a compressor and an internal combustion engine, a centrifugal governor for said engine, a device for setting the governor whereby the speed of the engine may be limited to a predetermined maximum, a fluid operated regulating device adapted to be actuated by a rise in discharge pressure due to a decreased air demand whereby the speed of the engine is reduced, a device for setting said regulating device for operation at a predetermined discharge pressure, and a connection between said fluid operated device and the governor having a double fulcrum, whereby the action of the governor will tend to counteract the action of the fluid operated regulating device.

2. In a compressor unit, the combination of a compressor and an internal combustion engine, a device for setting the governor whereby the speed of the engine may be limited to a predetermined maximum, a centrifugal governor for said engine, a fluid operated regulating device adapted to be actuated by a fall in discharge pressure due to an increased air demand whereby the speed of the engine is increased, a device for setting said regulating device for operation at a predetermined discharge pressure, and a connection between said fluid operated device and the governor having a double fulcrum, whereby the action of the governor will tend to counteract the action of the fluid operated regulating device.

3. In a compressor unit, the combination of a compressor and an internal combustion engine, a centrifugal governor for said en-

gine, means for setting the governor for maximum speed, a fluid operated regulating device adapted to be actuated by a rise or fall in discharge pressure, due to a decreased 5 or increased air demand, whereby the speed of the engine is reduced or increased and a connection between said fluid operated de-

vice and the governor having a double fulcrum whereby the action of the governor will tend to counteract the action of the 10 fluid operated regulating device.

In testimony whereof I have signed this specification.

JOSEPH W. JONES.

Certificate of Correction.

It is hereby certified that in Letters Patent No. 1,550,964, granted August 25, 1925, upon the application of Joseph W. Jones, of Corning, New York, for an improvement in "Automatic Speed Regulators," an error appears in the printed specification requiring correction as follows: Page 2, lines 113 to 115, strike out the words and comma "a device for setting the governor whereby the speed of the engine may be limited to a predetermined maximum," and insert the same to follow after the word "engine", line 116; and that the said Letters Patent should be read with this correction therein that the same may conform to the record of the case in the Patent Office.

Signed and sealed this 13th day of October, A. D. 1925.

[SEAL.]

KARL FENNING,
Acting Commissioner of Patents.
